UNITED STATES PATENT OFFICE.

EDWARD B. CAMPBELL, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

ROTARY PIVOTED HAMMER.

1,413,652.

Specification of Letters Patent. Patented Apr. 25, 1922.

Application filed June 28, 1920. Serial No. 392,419.

To all whom it may concern:

Be it known that I, EDWARD B. CAMPBELL, a citizen of the United States, residing at St. Louis, State of Missouri, have 5 invented certain new and useful Improvements in Rotary Pivoted Hammers, of which the following is a specification.

This invention relates to certain new and useful improvements in rotary pivoted hammers, the peculiarities of which will be 10 fully described and claimed.

The main object of my invention is the provision of a simple efficient form of hammer that may be readily made from a commercial shape of bar steel and will operate 15 efficiently in a grinding mill on stock food or other materials.

In the accompanying drawing on which like reference letters indicate corresponding 20 parts, Fig. 1 represents a vertical sectional view transversely to the shaft and just inside the end disc of a grinding mill embodying my improvements; Fig. 2 a sectional elevation on the line 2—2 of Fig. 1 with part 25 of the rotor shown in side view; and Fig. 3 a detail perspective view of the preferred form of my hammer.

The letter A designates a shaft for a grinding mill having a casing B and a cage 30 C. On the shaft is mounted a series of discs D through which pass hammer rods E parallel to the shaft which pivotally support the hammers which in my preferred construction consist of a shank portion F provided with a pivotal hole G at one inner end 35 and having the other end turned out substantially at right angles to the shank as shown at H. This turned-out end is therefore parallel to the pivotal axis of rotation 40 and when two pieces thus formed are placed with their shanks back to back and their bent out-ends H extending in opposite directions, they constitute a T-form of hammer as shown in Figs. 2 and 3. The centrifugal force acting upon the hammers when 45 so mounted as in the figures will cause them to maintain their radial position and except under extreme resistance of material being acted on, when they will fly backwards be-

tween the said discs D. It is preferred in 50 order to keep the bent out head ends in fixed alignment to fasten the shanks together, by a rivet I, at some point in the shanks between the pivot hole and the bent-out head ends. The rivet holds the shank 55 portions firmly back to back and co-operates with the hammer rod to maintain the bent-out head ends in alignment, without other connection between the two symmetrical pieces forming the pivoted hammer. The 60 rivets should be countersunk to prevent interference of the ends with the disc plates D. I have shown a rivet as constituting the only fastening means but other form of fastening may be employed. When thus 65 riveted or secured together as shown in Fig. 3, the rigid T-form of hammer head is maintained by the rod and rivet, and produces a slicing action by its bent out head ends and acts efficiently upon the material 70 being reduced.

In Fig. 2 the rows of hammers are alternately arranged so that the hammer in one row comes opposite the openings between the two hammers in the next adjacent rows 75 and thus secure uniformity of grinding action.

I claim:

An improved rotary pivoted hammer consisting of two symmetrical thin flat bar elements forming shanks placed flat side to flat side, and each having a head bent out at substantially right angles to the flat side of the shank in opposite directions,—said bent out head portions having the thin edge 80 of the bar in one head aligned with the thin edge of the other head and forming a thin cutting edge one-half the thickness of the double shank,—the inner ends of each shank having an open hole near the inner end registering with an open hole in the other adjacent shank for pivotal mounting, and means 85 for binding said elements together so as to move as a unit.

In testimony whereof I have affixed my 90 95 signature.

EDWARD B. CAMPBELL.
